(57) **CLAIM**

The ornamental design for a collapsible bucket as shown and described.

DESCRIPTION

FIG. 1 is a top perspective view of the collapsible bucket in an expanded or open condition;

FIG. 2 is a top perspective view thereof in a closed or collapsed condition;

FIG. 3 is a rear view thereof;

FIG. 4 is a front view thereof;

FIG. 5 is a first side view thereof;

FIG. 6 is a second side view thereof;

FIG. 7 is a top view thereof; and,

FIG. 8 is a bottom view thereof.

The dashed lines are for the purpose of illustrating elements of the collapsible bucket and forms no part of the claimed design.
